SEPARATOR SHIELD

Richard K. Whitehead, Atlanta, Ga.

Application June 3, 1947, Serial No. 752,089

3 Claims. (Cl. 57—108)

1

My invention relates to separator shields of the kind employed on spinning frames, twisting frames, and the like.

In the past, separator shields, and full assemblies of separator shields as for spinning frames, have been relatively cumbersome. In some cases, these shields have been made from steel stampings, slotted to reduce the weight of an assembly of separator shields. Such a structure may be objectionable, for the reason that the slots tend to roughen the yarn which is being spun. In other attempts to reduce the weight of an assembly of separator shields, the complete shield has been formed in a die-casting operation, utilizing aluminum or other light alloys. The latter construction has overcome previous objections, but not without presenting a problem of its own. This problem concerns a high percentage of structural failures, for the die-cast shield will not stand shock or bending and straightening without breakage.

It is, accordingly, an object of my invention to provide an improved separator shield of the character indicated.

It is another object to provide an improved separator shield that will be light in weight, that will not roughen the yarn being spun, and that will be sufficiently flexible to absorb shock, bending, and straightening without breakage.

It is in general an object of my invention to provide a light-weight separator shield which will have inherently long life and which may not impair the quality of product made by the machine to which the shield is adapted.

Other objects and various further features of the invention will be pointed out or will occur to those skilled in the art from a reading of the following specification in conjunction with the accompanying drawings. In said drawings:

Fig. 1 is a fragmentary plan view of an assembly of separator shields incorporating features of the invention, shown in application to a ring rail of a spinning or twisting frame;

Fig. 2 is an enlarged sectional view taken substantially in the plane 2—2 of Fig. 1;

Fig. 3 is a perspective view of a separator shield according to the invention, shown mounted on a supporting bar;

Fig. 4 is a fragmentary sectional view taken through the plane 4—4 of Fig. 1;

Fig. 5 is an enlarged sectional view taken in the plane 5—5 of Fig. 4; and

Fig. 6 is a vertical sectional view through a permanent mold to illustrate a preferred method of fabricating a separator shield according to the invention.

Briefly stated, my invention contemplates an improved separator-shield construction, in which the blade is formed of stamped sheet material that is preferably resilient and light in weight;

2

a hub for the shield may be cast or molded integrally with the blade. In the form to be described, the blade is preferably of light-weight aircraft-alloy aluminum sheet, stamped into a desired shape, with an opening to be employed for securing the same to its supporting hub. The hub is also preferably of aluminum and is cast integrally with the part of the blade which includes the opening, so that the completed shield may be a rigid, integral assembly of the blade with the hub.

Referring to the drawings, my invention is shown in application to one of a plurality of separator shields 10, which may be held in spaced relation on a longitudinally extending supporting bar 11 running, say, the length of a spinning or twisting frame. The bar 11 may be held by a plurality of spaced brackets 12, secured as by bolts 13 to the ring rail 14 of the machine. The separator shields 10 may be located between rings 15 in order to separate (in a non-interfering relationship) the yarns being spun or twisted on spindles (not shown) within the rings 15. The brackets 12 may be formed with suitable inner slotted contours 16 to retain the supporting bar 11 in a first position (see the solid-line outlines of Fig. 2) separating the spindles in rings 15, or in a second position (see dot-dash or phantom outlines of Fig. 2) for retracting the separator shields, as in a doffing or donning operation.

In accordance with the invention, the separator shields 10 are formed from essentially two elements. The first element or blade 17 may be of sheet material, and preferably the blade 17 is a stamping from a light-weight resilient metal, such as aircraft-alloy aluminum. The second element of my novel shield assembly is a hub 18 for use in securing the same to the bar 11. The hub 18 is preferably cast or molded so as to be integral with the blade 17, and in the form shown, the hub 18 includes two side members 19—20 to embrace portions of opposite sides of the blade 17. The hub casting is also preferably of aluminum alloy or other light-weight material.

The blade 17 preferably includes one or more openings 21, to be flooded in the process of molding the hub 18 to the blade 17. Since the side members 19—20 are thus integrally bonded together through the openings 21 and over extended parts of the side surfaces of the blade 17, the hub 18 may be securely locked (in effect, as one piece) with the blade 17. To complete the shield assembly, the hub 18 may also be formed with a supporting yoke having a bar-engaging groove or slot 22 and with a tapped hole to receive securing means in the form of a screw 23 passing through the bar 11 and engaging the hub 18.

In a preferred form, the ruggedness of my separator shield assembly is considered to be enhanced by locating the openings 21 near a cor-

ner 24 of the blade 17, said corner 24 being defined by side elements making a relatively sharp angle with each other. Furthermore, a slot 25 formed in the blade 17 may provide additional depth for the tapped hole into which the screw 23 is to be secured. Clearly, such additional depth as permitted by slot 25 promotes increased rigidity of the mounting of the shield 10 to the bar 11, as well as increasing the strength of the shield assembly.

In accordance with the invention, the hub 18 and blade 17 may be formed in a relatively simple molding operation, which, for example, may employ a permanent mold 26. In Fig. 6, I show one half of such a mold 26, with the blade 17 set into overlapped relation with a part of the cavity 27 used to define the hub 18. The permanent mold 26 preferably provides an extended tail opening 28 to assure a complete filling of the hub cavity and hence an effective bond between the hub 18 and the blade 17. Preferably, the tail opening 28 provides a feed passage for the molten metal to that part of hub 18 which becomes the groove 22; with such construction, it will be clear that burrs or other finish marks resulting from removal of the tail after a casting operation may not impair the finished appearance of a mounted separator shield 10.

If desired, the mold cavity may be such as to form the side elements 19-20 of hub 18 as relatively thin members. In such event, however, I prefer also to include an enlarged or bulbous portion 29 on each side of the side members 19-20, in general alignment with the securing means 23. The bulbous portions 29 will thus be understood to provide added security and reinforcement for a seating of the screw 23 in the hub 18.

It has been indicated above that the blade stamping 17 may include an opening or slot 25 to receive the tapped hole for screw 23. In many cases, however, it will be clear that the nature of the materials of blades 17 and hubs 18 may permit the drilling and tapping of the hole for screws 23 not only through the hub 18 but also into the part 25 of blade 17. In such event, a special slot 25 in the blade 17 would be unnecessary.

It will be appreciated that I have described a unique separator-shield construction having features which tend to avoid objections raised against prior-art constructions. The blade is

resiliently yieldable so as to resist breakage and to absorb shocks; the blade may be of extremely smooth finish so as in no way to impair the quality of the spun yarn; and an assembly of my separator shields may be of such light weight, when compared with many prior structures, as to increase the operating efficiency of the machine by reducing shutdown time for separator-shield replacements.

10 While I have described my invention in detail for the preferred form shown, it will be understood that modifications may be made within the scope of the invention as defined in the appended claims.

15 I claim:

1. In a separator shield for spinning frames and the like; a separator plate of sheet material, said plate having an anchoring means; a hub formed integrally and in one piece with said separator plate and embracing said anchoring means and both sides of said plates adjacent said anchoring means; said hub having a part to be secured to a support.

2. In the combination defined in claim 1, said hub having an aperture extending inwardly in a direction generally parallel to said plate and extending inwardly beyond the adjacent edge of the plate embraced by said hub adjacent said aperture.

3. In a separator shield for spinning frames and the like; a separator plate of sheet material, said plate having an aperture transversely therethrough, a hub formed integrally and in one piece with said plate and embracing opposite sides of said plate, said hub having an integral anchoring bridge extending through said aperture and between the parts embracing opposite sides of said plate, said hub having a part to be secured to a support.
